UNITED STATES PATENT OFFICE.

DANIEL T. MACLEOD, OF RACINE, WISCONSIN, ASSIGNOR TO PERFEX CORPORATION, OF RACINE, WISCONSIN, A CORPORATION OF WISCONSIN.

RADIATOR.

Application filed April 25, 1927. Serial No. 186,306.

This invention relates to heat interchangers and more particularly to radiators for internal combustion engines, air compressors, Diesel engines, etc.

5 The main objects of this invention are to provide an improved form of radiator particularly adapted for use with heavy duty internal combustion engines and cooling systems and having increased efficiency due to 10 more uniform distribution of the flow of cooling medium through the radiator; to provide an improved arrangement of radiator core sections; and to provide an improved form of tubular radiator wherein the water 15 is caused to pass twice through the current of air induced by the fan thus forming a multiple pass radiator.

An illustrative embodiment of the invention is shown in the accompanying drawings 20 wherein:—

Fig. 1 is a front elevation of a sectional radiator for automobiles.

Fig. 2 is a side elevation thereof.

Fig. 3 is a sectional detail of a modified 25 form of header tank.

The least effective cooling area of radiators for internal combustion engines is in the center of the core section. This is due to the fact that the fan does not draw the air with as 30 much velocity at the center of the core section as it does nearer the outside of the core section. Furthermore, the engine block creates a back pressure which establishes air eddies.

35 In the usual forms of radiators, the water intake is through the upper hose connection secured to the upper header near its middle portion and the outlet is through the lower hose connection secured to the lower 40 header near its middle portion. As the water is circulated by the water pump, a current is established between the intake and outlet hose connections and thus naturally follows the line of least resistance and most of the 45 circulating water flows through the central portion of the core where the air currents are least effective.

In the herein described invention increased 50 cooling efficiency is obtained by subdividing the core into two or more main sections each made up of multiple units and arranging the inlet and outlet and the communicating passages so that the current of water is caused to flow more uniformly through each of the 55 several core units. This is accomplished by

having inlets in the upper headers of each main section adjacent opposite corners thereof and outlets in their respective lower headers adjacent the corners diagonally opposite their respective inlets. A conduit at the side 60 of the intake of one header and the outlet at the side of the other header provides communication between the lower header of one main section and the upper header of the other main section. In this manner, a greater 65 volume of the water is caused to pass through the side portions of the main sections which portions are the most efficiently cooled.

In the construction shown, an upper header 1 is either divided into two compartments 2 and 3 by a longitudinally disposed wall 4 as shown in Fig. 3, or there may be two separate compartments as shown in Fig. 2. The compartments 2 and 3 of the upper header 1 are provided with filler necks 5, communicating 70 with the interior thereof for filling the radiator with water. The filler neck is screw-threaded for attaching a closure cap 6. A lower header 7 is similarly divided into two 75 separate compartments 8 and 9 which may likewise be of the integral type as shown in Fig. 3.

A plurality of vertically disposed radiator core units 11 are secured interchangeably between the upper and lower headers by bolts 80 12 and provide communication between the upper compartment 2 and the lower compartment 8. A plurality of similar core units 13 provide communication between the compartment 3 of the upper header and the compartment 9 of the lower header and to which they are secured by bolts 12. Side frame members 14 are secured between the upper and lower headers to provide for structural 85 strength and rigidity.

Water from the engine is discharged into the radiator through an upper hose connection pipe 15, and elbow 16 which communicate with the compartment 3 of the upper header 1. Compartment 8 of the lower header 100 is similarly connected with the lower hose connection, not shown, by a pipe 17 and an elbow 18, providing the water outlet on the same side of the radiator as the inlet.

The two multiple unit core sections, front 105 and rear as indicated by the letters F and R communicate mutually through an upright, slightly inclined conduit or pipe 19 which is on the side of the radiator opposite the inlet and outlet hose connections and extends from 110

compartment 9 of the lower header to compartment 2 of the upper header, or one of the side frame members 14 may be constructed to provide a conduit between the several core sections. The lower end of communicating pipe or conduit 19 connects with the compartment 9 in the lower header through an elbow 20 to which it is threaded and a pipe nipple 21 screwed in a threaded port in the wall of 10 said compartment. The upper end of the conduit 19 connects with the compartment 2 in the upper header through a similar connection comprising a pipe nipple 23, elbow 24 and a union 25.

15 The arrows indicate the general direction of this more uniform flow of the cooling medium through the several radiator sections and core units. It will be observed that the flow of water entering the intake is through 20 the compartment 3 downward through the core units 13 of section R to the compartment 9 from which it flows upwardly through the pipe 19 to the compartment 2 and thence 25 downward through the core units 11 of section F to the compartment 8 and out through the outlet pipe 17 to the lower hose connection. It will therefore be seen that the circulating water in its flow through the two radiator core sections R and F and their respective 30 core units 13 and 11 will be cooled more efficiently than in structures now in common use inasmuch as a greater volume is caused to pass through those portions of the radiator which are the most efficiently cooled.

35 While but one specific embodiment of this invention has been herein shown and described, it will be understood that numerous details of the construction shown may be altered or omitted without departing from 40 the spirit of this invention as defined by the following claims.

I claim:

1. In a heat interchanger, a pair of similar core sections disposed one behind the other 45 relatively to the direction of air flow and in substantially close set relation and fluid conducting means connecting the lower portion of one core section and the upper portion of the other core section.
- 50 2. In a heat interchanger, a pair of similar core sections disposed one behind the other relatively to the direction of air flow, a top header and a bottom header common to said core sections, and a conduit connecting said 55 headers for providing communication between the lower portion of the rear core section and the upper portion of the front core section, said headers each having compartments for said core sections respectively.
- 60 3. In a heat interchanger, a pair of core sections disposed one behind the other relatively to the direction of air flow, top and bottom header means therefor, an intake means for the upper portion of one core sec-

tion adjacent one side thereof, an outlet 65 means for the lower portion of the other core section adjacent the same side, and a conduit on the side opposite from the inlet and outlet means leading from the lower header of the core section having the intake 70 to the upper header of the core section having the outlet.

4. In a heat interchanger, a pair of core sections disposed one behind the other relatively to the direction of air flow, top and bottom header means therefor, an intake for 75 one of said sections adjacent an upper corner, an intake for said other section adjacent the opposite upper corner, an outlet for said first mentioned section adjacent the corner diagonally opposite from its intake, an outlet for said second mentioned section adjacent the corner diagonally opposite its intake, and means providing communication between the 80 two core sections.

5. In a heat interchanger, heat transfer means having several similar parts exposed in succession to the same air flow, and a conduit for providing series flow communication 90 between the bottom positioned outlet portion of one part and the top positioned inlet portion of another part, whereby the same water will traverse said parts successively and in the same direction.

6. In a heat interchanger, a core section having several similar parts exposed in succession to the same air flow, divided common headers whose several divisions each communicate 100 respectively with different core parts, and a conduit for providing series flow communication between the bottom outlet portion of one part and the top inlet portion of another part, whereby the same water will traverse said parts successively.

7. In a heat interchanger, heat transfer means having several parts exposed to the same air flow, divided integral headers whose several divisions each communicate respectively with different core parts and a conduit 110 for providing communication between the outlet portion of one part and the inlet portion of another part, whereby the same water will traverse said parts successively.

8. A radiator for internal combustion engines, comprising heat transfer means including a pair of similar core sections disposed one behind the other relatively to the direction of air flow, upper and lower headers for the core sections, and a conduit for providing series communication between the lower header of one core section and the upper header of the other core section, and also downward movement of fluid in both of said core sections.

Signed at Chicago this 21st day of April, 125
1927.

DANIEL T. MACLEOD.
